UNITED STATES PATENT OFFICE.

JACOB CLOVE, OF PENDLETON, OREGON.

AUTOMATIC LEVELING COMBINED HARVESTER.

No. 905,985.

Specification of Letters Patent.

Patented Dec. 8, 1908.

Application filed April 26, 1907. Serial No. 370,501.

To all whom it may concern:

Be it known that I, JACOB CLOVE, a citizen of the United States, and a resident of Pendleton, Umatilla county, Oregon, have invented a new and useful Automatic Leveling Combined Harvester, of which the following is a specification, reference being had to the accompanying drawings as constituting a part thereof.

10 My invention relates to traveling harvesters and has for its object to adapt the same to be more effectively used on side hills.

To this end my invention has for its purpose to so arrange the machine and its wheeled support that the housing containing the harvesting or thresher mechanism will substantially be maintained in vertical position, whatever the transverse incline of the 20 ground over which the machine is traveling, so as to avoid any undue strain on the bearings of the working parts and facilitate the work of the latter.

I attain my object by the arrangement and 25 combinations of parts as hereinafter described.

Figure 1 of said drawings is a partial plan or top view of my combined harvester; Fig. 2 is a rear-end view thereof; Fig. 3 is a like 30 rear-end elevation, showing my machine as operating on a steep side hill; Figs. 4 and 5 are details of construction described in the body of the specification; and Fig. 6 is a perspective detail of one of the wheel frames.

35 The letters designate the parts described.

The running gear of my machine comprises a body-frame, consisting of timbers a , a' , a'' . Near the lateral ends of said body-frame are pivoted, by suitable pivot bearings 40 c^2 , wheel-frames b , b' , including boxes d , d' , in which the axle ends of the wheels c , c' , are journaled. The wheel-frames b , b' are substantially alike in construction. Each of 45 said wheel-frames comprises a horizontal rectangular frame b^2 , on which are mounted vertical members b^3 , b^4 , and affixed cross-wise on the latter is a top member b^5 , the parts being braced and bolted as required. Centrally mounted on the frame b^2 are the 50 axle-boxes d , d' .

The frame e of the body or housing enclosing the harvesting-mechanism, is pivoted, in front and rear, to the cross-timbers a , a' , of the vehicle body, by suitable pivot 55 bearings of which only the rear-bearing f can be seen in the drawings.

In the front part of the vehicle body is affixed an arched member or bar n , provided on one face with a series of cogs or teeth n' . Said member n is conveniently constructed 60 by taking two bars n^2 , n^3 , curved and arranged concentrically, and affixed intermediate of the upper segments thereof are a plurality of radially arranged cog-like rods n^4 , as shown in the detail, Fig. 4. 65

In the upper portion e' of the frame of the housing e is journaled, in bearings, e^2 a shaft o' ; fast on the lower end of said shaft is a pinion o , and fast on the upper end thereof is a bevel-gear p . Meshing with the latter are a 70 pair of bevel pinions q , q' , which are loosely mounted on a horizontally journaled shaft q^2 , and are provided on their outer faces with integral hollow-faced bevel-rimmed friction gears s , s' . The latter are held against shifting longitudinally on their shaft q^2 by set-screws v , extending into circumferential grooves made on said shaft. A detail of this arrangement is shown in Fig. 5. By observing the latter, it will be seen that the shaft q^2 75 is made with splines q^6 at its ends, on which are slidably mounted the friction gears r , r' , having bevel rims adapted to engage with the hollow faces of the friction gears s , s' , when moved into contact with the latter by 80 the operation of the pivoted yoke, t . It will also be noted that the movement of one of the friction gears r , r' into contact with its corresponding friction gear (s or s') will simultaneously move the other gear (r or r') 85 out of such contact. The shaft q^2 has an extension q^7 , on which is rigidly mounted a sprocket-gear q^8 , operatively connected by a sprocket-chain q^9 (of which a part only is shown) with some convenient sprocket-gear 90 (not shown) on the projecting end of one of the driven shafts of the harvesting-mechanism. The yoke t is supported by an arm t' , rigidly mounted on a shaft t^2 , journaled in suitable boxing supported on the frame-timbers e' , and on the front end of the shaft t^2 is rigidly mounted the pendent rod u of a pendulum-weight u' . 95

In alignment with the wheel-axes, the housing e is provided with a rectangular frame g , having exterior portions h , respectively curved on their edges to constitute segments of the same circle. Exterior of the curved portions h are affixed slotted guide-bars i , in which are slidably held cross-heads j , connected by hinged joint k , to arms l , rigidly affixed on the inner sides of the wheel- 100 105 110

frames b, b' . Thus the jointed connections between the wheel-frames and the housing frame of the machine cause the wheel-frames to follow the movement of the former, 5 or in other words, cause the wheel-frames to be moved up and down in correspondence with the movement of the housing frame, due to a transverse incline of the ground over which the harvester is being operated.

10 Supposing now the shaft q^3 to be continuously driven during the operation of my harvester, it will be apparent that so long as the harvester travels over substantially level ground, there will be no effect, but as soon as 15 the harvester begins to travel over ground sloping to some degree, the pendulum will assume a relative position, thereby operating the yoke t , so as to bring one or the other of the friction gears r, r' into operative contact 20 with one of the corresponding friction gears s, s' ; upon which the power of the shaft q^3 will be transmitted through the bevel-gears q, q' , to the gear p , driving the latter during the period of time that the pendulum remains 25 out of plumb; and thus driving the shaft o' , and thereby the pinion o , which, meshing with the arched rack-bar n , will move the housing-frame relatively to the incline of the body-frame due to a transverse slope of the 30 ground, and thereby maintain the housing-frame in substantially vertical position notwithstanding said slope of the ground. It is further apparent that after the housing-frame has been moved relatively to the incline of the ground, and the latter again begins to return to a more horizontal plane, the 35 pendulum will make a relative movement and in so doing operate the described devices, and thereby cause a corresponding movement of the housing-frame. And as a result of the described action, the body or housing of my machine inclosing the harvesting devices will maintain a substantially vertical position throughout the operation of 40 my machine, and the bearings of its operating parts relieved of any undue strain.

The front ends of the members e^3 of the housing frame extend over and are supported by the fifth wheel of the running gear, (not 50 shown).

To restrain the lower end of the pendulum in case of a forward or rearward dip of my machine, while in action, I provide a pair of transverse guide rods w between which the 55 pendulum swings. To increase the arc of motion of the housing-frame the corners x, x' thereof are beveled.

I claim:

1. In a combined harvester, the combination of a body-frame, wheel-supports pivoted to the lateral ends thereof, a housing-frame pivoted to the body-frame, intermediate of the wheel-supports, a transversely oscillating member and means thereby controlled adapted to move said housing-frame

relatively to the transverse incline of the body-frame, so as to maintain said housing-frame in perpendicular position, and movable connections between said housing-frame and the wheel-supports, adapted to 70 cause the latter to follow said relative movement of the housing-frame.

2. In a combined harvester, the combination of a body-frame, wheel-supports pivoted to the lateral ends thereof, a housing-frame pivoted to the body-frame, intermediate of the wheel-supports, a transversely oscillating pendulum and means thereby controlled adapted to move said housing-frame relatively to the transverse incline of 75 the body-frame, so as to maintain said housing-frame in perpendicular position, and movable connections between said housing-frame and the wheel-supports adapted to cause the latter to follow said relative movement of the housing-frame.

3. In a combined harvester, the combination of a body-frame, wheel-supports pivoted to the lateral ends thereof, a housing-frame pivoted to the body-frame, intermediate of 90 the wheel-supports, a transversely oscillating pendulum and means thereby controlled adapted to move said housing-frame relatively to the transverse incline of the body-frame, so as to maintain said housing-frame in perpendicular position, vertical 95 circle segments affixed to the exterior of the housing-frame, and movable connections between said circle segments and the wheel-frames, adapted to cause the latter to follow 100 said relative movement of the housing-frame.

4. In a combined harvester, the combination of a body-frame, wheel-frames pivoted to the lateral ends thereof, a housing-frame 105 pivoted to the body-frame, intermediate of the wheel-frames, a transverse arched bar, affixed to the lateral ends of the body-frame and provided with cogs, a revoluble shaft and a pinion thereon, meshing with said cogs 110 of the arched bar, a driven shaft, means, including clutching elements and a transversely oscillating pendulum, the latter arranged to control such clutching elements, whereby the power of said driven shaft is 115 transmitted to drive said revoluble shaft, and the housing-frame is moved relatively to the transverse incline of the body-frame, and maintained in perpendicular position, and movable connections between said housing-frame and the wheel-frames adapted to cause the latter to follow said relative movement of the housing-frame.

5. In a combined harvester, the combination of a body-frame, wheel-frames pivoted 125 to the lateral ends thereof, a housing-frame pivoted to the body-frame, intermediate of the wheel-frames, a transverse arched bar, affixed to the lateral ends of the body-frame and provided with cogs, a revoluble shaft 130

and a pinion thereon, meshing with said cogs of the arched bar, a driven shaft, means, including clutching elements and a transversely oscillating pendulum, the latter arranged to control such clutching elements, whereby the power of said driven shaft is transmitted to drive said revolute shaft, and the housing-frame is moved relatively to the transverse incline of the body-frame and maintained in perpendicular position, vertical circle segments affixed to the exterior of the housing-frame, and movable connections between said circle segments and the wheel-frames adapted to cause the latter to follow said relative movement of the housing-frame.

6. A combined harvester, comprising a body-frame, wheel-frames pivoted to the lateral ends thereof, a housing-frame pivoted to the body-frame, intermediate of the wheel-frames, a transverse arched bar consisting of two concentric members, a plurality of radially disposed cog-like rods in the upper part of said arched bar, a revolute shaft, and a pinion thereon, meshing with said cog-like rods, a driven shaft, means, including clutching elements and a transversely oscillating pendulum, the latter arranged to control such clutching elements, whereby the power of said driven shaft is transmitted to drive said revolute shaft, and the housing-frame is moved relatively to the transverse incline of the body-frame, and maintained in perpendicular position, and movable connections between said housing-frame and the wheel-frames adapted to cause the latter to follow said relative movement of the housing-frame.

7. A combined harvester, comprising a body-frame, wheel-frames pivoted to the lateral ends thereof, a housing-frame pivoted to the body-frame, intermediate of the wheel-frames, a transverse arched bar consisting of two concentric members, a plurality of radially disposed cog-like rods in the upper part of said arched bar, a revolute shaft, and a pinion thereon, meshing with said cog-like rods, a driven shaft, means, including clutching elements and a transversely oscillating pendulum, the latter arranged to control such clutching elements, whereby the power of said driven shaft is transmitted to drive said revolute shaft, and the housing-frame is moved relatively to the transverse incline of the body-frame, and maintained in perpendicular position, vertical circle segments affixed to the exterior of the housing frame, and movable connections between said circle segments and the wheel-frames adapted to cause the latter to follow the housing-frame in its movement relative to the transverse incline of the body-frame.

8. A combined harvester, comprising a body-frame, wheel-frames pivoted to the lateral ends thereof, a housing-frame pivoted to the body-frame, intermediate of the wheel-frames, and a transverse arched bar affixed to the lateral ends of the body-frame, and provided with cogs, a vertical shaft and a pinion thereon, meshing with said cogs, a beveled gear on said vertical shaft, a horizontal driven shaft, clutching elements horizontally movable on the ends of said horizontal shaft, a pivoted yoke, and a pendulum controlling the same, the former arranged to move said clutching elements into and out of operative position, a pair of beveled pinions loosely mounted on said horizontal shaft, intermediate of and provided respectively with parts adapted to be engaged by said clutching elements, when the latter are moved into contact therewith by the swing of said pendulum, and movable connections between said housing-frame and the wheel-frames, adapted to cause the latter to follow the housing-frame in its movement relative to the transverse incline of the body-frame.

9. A combined harvester, comprising a body-frame, wheel-frames pivoted to the lateral ends thereof, a housing-frame pivoted to the body-frame, intermediate of the wheel-frames, a transverse arched bar affixed to the lateral ends of the body-frame, and provided with cogs, a vertical shaft and a pinion thereon, meshing with said cogs, a beveled gear on said vertical shaft, a horizontal driven shaft, clutching elements horizontally movable on the ends of said horizontal shaft, a pivoted yoke, and a pendulum controlling the same, the former arranged to move said clutching elements into and out of operative position, a pair of beveled pinions loosely mounted on said horizontal shaft, intermediate of and provided respectively with parts adapted to be engaged by said clutching elements, when the latter are moved into contact therewith by the swing of said pendulum, and movable connections between said housing-frame and the wheel-frames, adapted to cause the latter to follow the housing-frame in its movement relative to the transverse incline of the body-frame.

10. A combined harvester, comprising a body-frame, wheel-frames pivoted to the lateral ends thereof, a housing-frame pivoted to the body-frame, intermediate of the wheel-frames, a transverse arched bar affixed to the lateral ends of the body-frame, and provided with cogs, a vertical shaft and a pinion thereon, meshing with said cogs, a beveled gear on said vertical shaft, a horizontal driven shaft, clutching elements horizontally movable on the ends of said horizontal shaft, a pivoted yoke, and a pendulum controlling the same, the former arranged to move said clutching elements into and out of operative position, a pair of beveled pinions loosely mounted on said horizontal shaft, intermediate of and provided respectively with parts adapted to be engaged by said clutching elements, when the latter are moved into contact therewith by the swing of said pendulum, vertical circle segments affixed to the exterior of the housing frame, and movable connections between said circle segments and the wheel-frames adapted to cause the latter to follow the housing-frame in its movement relative to the transverse incline of the body-frame.

11. A combined harvester, comprising a body-frame, wheel-frames pivoted to the lateral ends thereof, a housing-frame pivoted to the body-frame, intermediate of the wheel-frames, a transverse arched bar affixed to the lateral ends of the body-frame, and provided with cogs, a vertical shaft and a pinion thereon, meshing with said cogs, a beveled gear on said vertical shaft, a horizontal driven shaft, clutching elements horizontally movable on the ends of said horizontal shaft, a pivoted yoke, and a pendulum controlling the same, the former arranged to move said clutching elements into and out of operative position, guide bars restraining the oscillating pendulum to a transverse path, a pair of beveled pinions loosely mounted on said horizontal shaft,

4
shaft, intermediate of and provided respectively with parts adapted to be engaged by said clutching elements, when the latter are moved into contact therewith by the 5 swing of said pendulum, vertical circle segments affixed to the exterior of the housing-frame, and movable connections between said circle segments and the wheel-frames adapted to cause the latter to follow the housing-frame in its movement relative to the transverse incline of the body-frame.

11. A combined harvester, comprising a body-frame, wheel-frames pivoted to the lateral ends thereof, a housing-frame pivoted 15 to the body-frame, intermediate of the wheel-frames, the bottom transverse ends of the housing-frame being beveled for the purpose specified, a transverse arched bar affixed to the lateral ends of the body-frame, and provided with cogs, a vertical shaft and 20 a pinion thereon, meshing with said cogs, a beveled gear on said vertical shaft, a horizontal driven shaft, clutching elements hori-

zontally movable on the ends of said horizontal shaft, a pivoted yoke, and a pendulum controlling the same, the former arranged to move 25 said clutching elements into and out of operative position, guide bars restraining the oscillating pendulum to a transverse path, a pair of beveled pinions loosely mounted on said 30 horizontal shaft, intermediate of and provided respectively with parts adapted to be engaged by said clutching elements, when the latter are moved into contact therewith by the swing of said pendulum, vertical circle 35 segments affixed to the exterior of the housing-frame, and movable connections between said circle segments and the wheel-frames adapted to cause the latter to follow the housing-frame in its movement relative to 40 the transverse incline of the body-frame.
